United States Patent Office

Des. 212,671
Patented Nov. 12, 1968

212,671

JUG

Hans Peter Jurgens, San Francisco, Calif., assignor to Almaden Vineyards, Inc., San Francisco, Calif., a corporation of Delaware

Filed June 22, 1967, Ser. No. 7,567

Term of patent 14 years

(Cl. D9—48)

FIG. 1 is an elevational view of a jug, showing my new design;

FIG. 2 is an elevational view looking from the right of FIG. 1;

FIG. 3 is a top plan view; and

FIG. 4 is a bottom plan view thereof;

FIG. 5 is an elevational view showing a modified form of the jug;

FIG. 6 is an elevational view taken from the right of FIG. 5;

FIG. 7 is a top plan view; and

FIG. 8 is a bottom plan view thereof.

I claim:

The ornamental design for a jug, substantially as shown and described.
